UNITED STATES PATENT OFFICE

THEODORE KLAHRE, OF UNION CITY, NEW JERSEY, ASSIGNOR TO CONSOLIDATED TRIMMING CORPORATION, OF NEW YORK, N. Y., A CORPORATION OF NEW YORK

WEFT-DISENGAGING DEVICE FOR BULLION-FRINGE LOOM APPARATUS

Application filed November 8, 1929. Serial No. 405,635.

Generally, the invention relates to novel and useful improvements in the construction and consequent mode of operation of weft disengaging devices preferably adapted for bullion-fringe loom apparatus, the latter being of the type capable of producing simultaneously a number of widths of fringe by having groups of warp threads spaced apart and weft threads adapted to be interweaved respectively with each of said groups of warp threads. It is usual in this type of loom to mount weft-inserting hooks on the lay and to move the said hooks by positive actuating mechanism carried on the lay and partaking of the swinging of the lay. To accomplish the disengagement or knocking-off of the bullion strands or weft threads from their respective hooks when the strands have reached their critical positions preceding the formation of fringe, it has been a practice to utilize a series of hammers positioned in spaced relation with respect to their respective hooks, the hammers being fixedly mounted on a shaft attached to the breast beam of the loom, and the shaft itself being actuated to reciprocating and synchronous movement by motion communicators and converters with or without the cooperation of springs, the power for the said actuation being derived from the main driving shaft or otherwise.

My invention relates particularly to a weft disengaging device adaptable for use plurally on bullion-fringe loom apparatus of the character described such that each disengaging device, after an initial adjustment with its respective weft-inserting hook, operates statically, requiring no power and functioning free of timing or synchronization with the position of the said hook.

The main object of my invention is to provide a weft disengaging device which neither consumes power nor contributes its increment of vibration when the loom operates either at normal or high speed. A further object of my invention resides in the structure, arrangement of parts and mounting of my invention such that synchronization with the respective weft-inserting hooks is accomplished by a single and facile adjustment of

each disengaging device. Another object of my invention resides in means for so controlling the strands as they are released from their respective hooks as to insure a homogeneous twist throughout the entire length and to keep the finished fringe on the inside of the lay.

These objects and other advantageous ends in the structure, arrangement, combination and cooperation of the several parts of my invention are now to be described, reference being had to the accompanying drawings, wherein like reference characters designate corresponding parts throughout all the views.

Fig. I is a partial view in perspective, partly in section, of a bullion-fringe loom showing one of the groups of warp threads for the production of a single width of fringe, and contains my invention.

Fig. II is a sectional end elevation of Fig. I taken along the line II—II.

1 represents the lay of any well known bullion-fringe loom of the type aforeoutlined, and is provided with the ordinary slide bar 3 suitably mounted thereon. Secured to slide bar 3 by means of any conventional upright such as 7, is a weft-inserting hook 8. 5 is a suitable standard utilized on apparatus of the type herein and is affixed to lay 1, the said standard having laterally and removably secured thereto a reed 6 through which pass a number of warp threads, the group being designated in the accompanying drawings by reference character 12. 11 is the weft or the material for the strands of bullion in the manufacture of any width of fringe and is positionally adapted to be engaged by hook 8, as will be more fully described hereinafter.

2 represents the breast beam of the bullion-fringe loom of the type herein and has affixed thereon by any means such as screw attachment rod 4 preferably positioned on the upper surface, rear edge and along the longitudinal axis of the said beam.

It is to be noted that Fig. I and the description thus far is mostly fragmentary; that standard 5 is one of a series secured to lay 1 and situated therealong in alignment and at

definite intervals, that hook 8, weft 11 and warp-thread group 12 are respectively, plurally and appropriately arranged throughout the length of the loom apparatus for the simultaneous production of a number of widths of fringe. However, from the standpoint of disclosure, it suffices to describe the said apparatus with my invention appended thereto by a single set of elements in spaced relation and requisitional for the production of a single width of fringe.

Reference is now had to a preferred form of the weft disengaging arrangement comprising my invention in adaptation with bullion-fringe loom apparatus of the type described herein. Weft 11, warp thread group 12 and the weft engaging part of hook 8 all lie in the same plane of the horizontal when the beat-up by reed 6 is effectuated, the said plane being appropriately spaced above the surface plane of lay 1. 13, 14 and 15 are spines or fingers preferably parallel to each other and disposed transversely to the longitudinal axis of lay 1, the said fingers respectively projecting from spaced orifices of bearing rod 4 and being adjustably fixed thereto by any means such as set screws passing through the upper surface of the said rod 4 and bearing against the aforementioned fingers. Finger 13 at a small distance from its bearing is bent to an angle of declination, the rear terminal of the said finger developing preferably into a forward and upwardly turned hook, the rearmost portion of the said finger extending somewhat beyond the rear edge of the position of lay 1 at the time of the beat-up by reed 6. Spines or fingers 14 and 15 extend at their rear terminals to the rear edge of lay 1 at the time of the beat-up by reed 6, the said 14 and 15 respectively developing at their terminals into similar and adaptable conformations as shown in Fig. I of the accompanying drawings. 9 is an upright, preferably an inverted U rod affixed to the rear edge of lay 1 by any suitable means such as screw attachment, and is adapted to cooperate with the rearmost portion of finger 14 for a purpose to be hereinafter described.

In reference to the operation of the bullion-fringe loom of the type herein in adaptation with my invention, lay 1, actuated and mounted by suitable means not illustrated in the accompanying drawings, reciprocates transversely to its longitudinal axis, while slide bar 3 secured thereon is actuated to synchronous oscillation therewith, the motion of the said slide bar being longitudinal of the lay. At the backward movement of lay 1 in the oscillation or reciprocation of the same, hook 8 passes through the warp shed of warp thread group 12 to engage weft 11. The warp threads of group 12 are actuated in the customary manner for the production of sheds by heddle frames, the heddle frames and the operating means therefor

not being illustrated in the accompanying drawings. Weft 11 is similarly actuated by a heddle frame, not illustrated in the accompanying drawings, to raise and lower the said weft 11 in and out of the path of hook 8. On the return and forward movement of lay 1, hook 8 carries weft 11 to be interwoven with the group of warp threads and to form bullion strands. When hook 8 has carried weft 11 to the extreme position, the disengaging device or arrangement comprising my invention comes into play.

Reference is now had to the "modus operandi" of the weft disengaging device in conjunction with the bullion-fringe loom described herein, with attention paid to the relative positions of the elements as shown in Fig. I, the said Fig. I being representational of a period immediately preceding the disengagement of weft 11 from hook 8 by finger 15, this period being followed by the beat-up of weft 11 by reed 6. At the time of the beat-up, lay 1 is at its maximum forward position.

The weft engaging portion of hook 8 is preferably a development of the terminal thereof, being bent to the rear and at an angle of declination so that any bullion strand of weft 11 may be struck free of hook 8 by the upright part of finger 15. The said finger 15 by reason of its adjustable extension beyond breast beam 2 releases or knocks off the bullion strand of weft 11 from hook 8 as lay 1 in its reciprocation proceeds to its forward limiting position, as best understood from Fig. II of the accompanying drawings. Finger 14, similarly positioned and in spaced relation with finger 15, in cooperation with upright 9 momentarily thereafter enacts a tension service to weft 11 by temporarily vising a portion of the bullion strand between the posts of upright 9, this phenomenon assuring necessary tension on weft 11 for its beat-up in the web. Furthermore, the said tension service affords a lapse in time for the natural and homogeneous twisting of the released bullion strand throughout its length in the formation of fringe.

As already intimated, after the release of the bullion strand from hook 8, reed 6 produces the beat-up of any particular pick. To safeguard against the suspension of the manufactured width of fringe from the web proper, to prevent the component fringes from dragging or rubbing with the lay and extending beyond thereto, finger 13 heretofore described is provided. The said finger 13 assures a uniform rolling of the manufactured width of fringe without exposing the individual fringes to kinking, intertwining and unparallel relationship.

It is to be noted that fingers 13, 14 and 15 are adjustable relative to the position of hook 8 and the amplitude of lay 1.

Thus my invention presents a simple, eco-

onomic and easily accessible disengaging device comprising the most fundamental of elements, easily accessible for replacement and repair and being adjustable to the conditions aforementioned, and being free of dynamic synchronization with any particular position of the weft inserting mechanism. The disengaging device has already been in use and has been found to function perfectly.

I wish it understood that the embodiment of my invention is solely for purposes of disclosure herein and that there is no limitation to any specific construction in the disclosure; minor changes in size, shape and arrangement of parts, variations and modifications of details may all be resorted to without departing from the spirit of my invention nor enlarging its scope within the appended claims.

Having described my invention, what I now claim as new and desire to secure by Letters Patent of the United States is:

1. For a bullion-fringe loom apparatus of the character described for weaving a plurality of fringes having groups of warp threads spaced apart and weft threads adapted to be interweaved respectively with each of said groups of warp threads, including a lay and a weft engaging hook moving with the lay and having relative movement longitudinal thereto, a weft disengaging device comprising an adjustably fixed finger in spaced relation to the reciprocating lay adapted to release the weft from a hook thereon, a similar member similarly disposed and in spaced relation to the aforesaid finger, an upright affixed to the lay and cooperating with the said member to afford a momentary tension device for the weft, and a rest disposed in spaced relation to support the manufactured fringe.

2. For a bullion-fringe loom apparatus of the character described for weaving a plurality of fringes having groups of warp threads spaced apart and weft threads adapted to be interweaved respectively with each of said groups of warp threads, including a lay and a weft engaging hook moving with the lay and having relative movement longitudinal thereto, a weft disengaging device comprising an adjustably fixed finger in spaced relation to the reciprocating lay adapted to release the weft from a hook thereon, a similar member similarly disposed and in spaced relation to the aforesaid finger, and an upright affixed to the lay and cooperating with the said member to afford a momentary tension device for the weft.

3. For a bullion-fringe loom apparatus of the character described for weaving a plurality of fringes having groups of warp threads spaced apart and weft threads adapted to be interweaved respectively with each of said groups of warp threads, includ-

ing a lay and a weft engaging hook moving with the lay and having relative movement longitudinal thereto, in combination, a weft disengaging device comprising an adjustably fixed finger in spaced relation to the reciprocating lay and adapted to release the weft from a hook thereon, a similar member similarly disposed and in spaced relation to the afore-said finger, an upright affixed to the lay and cooperating with the said member to afford a momentary tension device for the weft immediately upon the latter's release from the above-mentioned hook, and a rest disposed in spaced relation to support the freshly manufactured portion of the fringe.

4. For a bullion-fringe loom apparatus of the character described for weaving a plurality of fringes having groups of warp threads spaced apart and weft threads adapted to be interweaved respectively with each of said groups of warp threads, including a lay and a weft engaging hook moving with the lay and having relative movement longitudinal thereto, in combination, a weft disengaging device comprising an adjustably fixed finger projecting in spaced relation to the reciprocating lay and adapted to release the weft from a hook thereon, a similar member similarly disposed and in spaced relation to the afore-said finger, and an upright affixed to the lay and cooperating with the said member to afford a momentary tension device for the weft immediately upon the latter's release from the above-mentioned hook.

5. For a bullion-fringe loom apparatus of the character described for weaving a plurality of fringes having groups of warp threads spaced apart and weft threads adapted to be interweaved respectively with each of said groups of warp threads, including a lay and a weft engaging hook moving with the lay and having relative movement longitudinal thereto, a weft disengaging device comprising an adjustably fixed finger projecting transversely and in spaced relation to the reciprocating lay, the said finger rearwardly terminating into a triangular formation with the upright portion thereof adapted to release the weft from a hook situated on the lay, a similar member similarly disposed and in spaced relation to the afore-said finger, an upright affixed to the rear of the lay and in spaced relation to cooperate with the said member to afford a momentary tension device for the weft immediately upon the latter's release from the above-mentioned hook, and a rest similarly disposed as the above-mentioned finger and member and in spaced relation thereto, the said rest terminating rearwardly into a forward and upwardly turned hook while near the front portion the rest is bent to an angle of declination, the

rest serving as a support for the freshly manufactured portion of the fringe.

6. For a bullion-fringe loom apparatus of the character described for weaving a plurality of fringes having groups of warp threads spaced apart and weft threads adapted to be interweaved respectively with each of said groups of warp threads, a weft disengaging device comprising an adjustably fixed finger projecting transversely and in spaced relation to the reciprocating lay, the said finger rearwardly terminating into a triangular formation with the upright portion thereof adapted to release the weft from a hook situated on the lay, a similar member similarly disposed and in spaced relation to the afore-said finger, and an upright affixed to the rear of the lay and in spaced relation to cooperate with the said member to afford a momentary tension device for the weft immediately upon the latter's release from the above-mentioned hook.

7. In a bullion-fringe loom apparatus of the class described, including a lay, a weft engaging hook mounted on the lay, and having relative movement longitudinal thereto, and fixed means to engage the weft and strip it from the hook when the lay moves in one direction.

8. In a bullion-fringe loom apparatus of the class described, including a lay, a weft engaging hook mounted on the lay, and having relative movement longitudinal thereto, and fixed means to engage the weft and strip it from the hook when the lay moves in one direction, said hook including a body and a bill extending from the body at an angle oblique thereto.

9. In a bullion-fringe loom apparatus of the class described, including a lay, a weft engaging hook mounted on the lay, and having relative movement longitudinal thereto, and fixed means to engage the weft and strip it from the hook when the lay moves in one direction, said means comprising a finger projecting transversely of the lay and terminating in a substantially triangular formation to engage the weft.

10. In a bullion-fringe loom apparatus of the class described, including a lay, a weft engaging hook mounted on the lay, and having relative movement longitudinal thereto, and fixed means to engage the weft and strip it from the hook when the lay moves in one direction, said means comprising a finger projecting transversely of the lay and terminating in a substantially triangular formation to engage the weft, and means for engaging the loop formed by the hook to support and tension said loop.

In testimony whereof, I have hereunto affixed my hand this 6th day of November, 1929, at 1440 Broadway, in the city, county and State of New York.
